COMBINATION TRAILER HITCH SUPPORT AND FISHING POLE HOLDER

Chester J. Sather, 1215 26th St., Ames, Iowa 50010

Filed July 27, 1970, Ser. No. 42,129

Term of patent 14 years

Int. Cl. D22—05

U.S. Cl. D22—22

FIG. 1 is a front view of a combination trailer hitch support and fishing pole holder showing my new design,

FIG. 2 is a side view thereof,

FIG. 3 is a top view thereof,

FIG. 4 is a bottom view thereof, and

FIG. 5 is a perspective view thereof shown in relation to trailer hitch with said hitch being in broken lines for illustration only.

I claim:

The ornamental design for a combination trailer hitch support and fishing pole holder, as shown and described.
